J. I. ASTROM

DEEP WELL PUMP HEAD

Filed July 5, 1921

UNITED STATES PATENT OFFICE.

JOHN I. ASTROM, OF FORT WAYNE, INDIANA, ASSIGNOR TO FORT WAYNE ENGINEERING & MANUFACTURING CO., OF FORT WAYNE, INDIANA, A CORPORATION OF INDIANA.

DEEP-WELL-PUMP HEAD.

Application filed July 5, 1921. Serial No. 482,354.

To all whom it may concern:

Be it known that I, JOHN I. ASTROM, a citizen of the United States, and resident of Fort Wayne, in the county of Allen and 5 State of Indiana, have invented certain new and useful Improvements in Deep-Well-Pump Heads; and I do hereby declare that the following is a full, clear, and exact description thereof.

10 My invention relates to new and useful improvements in head structures for pumps, and adapted more particularly for deep well pumps, similar to that which is disclosed in my former United States Patent Number 15 1,241,604.

The object of my present invention is to provide a structure of the class described in which the crank motion is so modified that a retarded movement is given the pump rod 20 at the beginning of its up and down stroke, whereby more time is given for the opening and closing of the pump cylinder valves, thereby resulting in a more quiet valve action and longer life of the valves and valve 25 seats.

A further object of my invention resides in the combination of two separate motions, operating in different directions, and so arranged that the objectionable inertia stresses causing vibrations of the moving parts are 30 greatly reduced.

It is still a further object of my invention to provide a pump head so arranged that the means for imparting motion to the pump 35 rod or underground parts can be readily and easily moved or disconnected in order to withdraw the same from the well without the usual necessity of moving the pump head upon its foundation. This is a disadvantage that is common in all pump heads of the character referred to and it is my object to overcome this with the structure herein-after referred to and illustrated in the 40 accompanying drawings, in which:—

45 Figure 1 is a vertical sectional view taken on the line 1—1 of Figure 3.

Figure 2 is a side elevational view of my improved pump head, and

Figure 3 is a front elevation of the same.

50 Referring now more particularly to the accompanying drawings, the numeral 1 designates a cast metal base plate provided in one end with a suitable passage to receive therethrough the vertically extending pump rod 2. The base plate 1 is further provided,

adjacent the end having the pump rod, with a pair of spaced sockets into which the lower ends of vertically extending tubular columns 3 are mounted, the upper ends of which are provided with bearing blocks 4, adapted to receive therein the end portions of a transversely and horizontally disposed crank shaft 5. One end of the crank shaft 5 projects through its bearing block and its projection is provided with a gear wheel 6, the latter meshing with a smaller gear 7, keyed to the end of a shaft 8, which is supported by suitable sleeve bearings 9 clamped about the vertically extending columns 3 and adjacent the bearing blocks 4. The 60 other end of the shaft 8 has keyed thereto a suitable driving element, preferably a belt wheel 10, by which the shaft is driven.

The structure hereinbefore referred to is similar in operation to that disclosed in 75 my former patent.

Slidably mounted upon the vertically extending columns 3, and between the base plate 1 and the sleeve bearings 9, is a pair of sleeves 11 which are connected by a cross 80 rod 12, this structure constituting what I shall hereinafter refer to as the cross head.

The crank shaft 5 has journaled on its intermediate or crank portion, a pitman 13, the lower end of which is provided with a 85 suitable bearing head to receive therein the cross rod 12 of the cross head.

The pitman 13 is further provided with an extension 14 arranged at right angles to its lower extremity, the end of which is 90 bifurcated and expanded in a common plane to form a fork between which the pump rod 2 operates.

The sleeves 11 of the cross head are further connected on the side adjacent the pump rod by a vertically disposed U-shaped member 15, the legs of which are secured to the sleeves by suitable bolts or the like 16. The intermediate portion or base of the U member has made integral therewith a 100 horizontally extending block 17, the same serving as a guide element for the upper end of the pump rod.

The upper end of the pump rod 2 has mounted thereon and retained by a nut 18, 105 a cross head 19, the end portions of which are provided with suitable extensions adapted to receive thereon for oscillatory movement the links 20, the lower ends of which are connected in a similar manner upon out- 110

wardly projecting pins or bosses carried by the furcations formed on the extension 14 of the pitman. The links are retained thereon by suitable locking means, such as 5 a nut or a cotter pin.

Referring to the drawings, it will be noted that the length of the extension 14 is equivalent to the distance from the pump rod to the cross rod 12, the purpose of which will 10 be more fully apparent as the description of of operation proceeds.

Briefly summarizing, the operation of my improved pump head is as follows: Assuming that the crank shaft 5 is rotating in the 15 direction as indicated by the arrow, and that the various parts are in position as illustrated in Figure 1. As the movement of the crank shaft 5 takes place the cross head 11 will move vertically upon the columns 3, 20 due to its connection with the crank shaft by the bell crank formed by the arms 13 and 14, the latter being connected by links to the pump rod. As the crank shaft 5 continues to move the cross head 11 will be moved up- 25 wardly until the crank within the shaft nearly approaches its highest point, thus further movement of the cross head is stopped at which time the pitman 13 swings over one side of its perpendicular to the 30 other. As the action just described takes place the pump rod is accordingly moved. Prior to the actual movement of the pitman 13 across its perpendicular the cross head 11 has reached such a position that the bell 35 crank, carried thereby, will swing upon its connections with the crank 5 and the links 20 and during this movement no motion is imparted to the pump rod. After this movement has taken place, the crank moves to 40 such a position that a slight downward movement of the cross head takes place. Thus it will be noted by reason of the links connected to the bell crank that the pump rod and the peculiar movement imparted to 45 the bell crank, the pump rod is caused to dwell at the beginning of its up and down strokes.

Therefore, it will be noted that the combination of movements caused by the regular 50 crank motion and the swinging motion of the bell crank at the end of its short arm, gives the desired motion to the pump rod which I claim as the salient feature of my invention.

Furthermore, it will be noted that by reason of this novel structure, the parts of the operating means or that part which is directly above the well can be readily disconnected and thrown out of the way, thus permitting the pulling out of the underground 60 parts without the usual necessity of remov-

ing the pump head or shifting it upon its base.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure 75 by Letters Patent, is:—

1. A pump of the class described comprising a base, and a pump rod extending therethrough, means for actuating said pump rod mounted upon said base, said means including a bell crank and its various connecting elements whereby a dwell is caused in the movement of said pump and at the beginning of its up and down stroke.

2. A pump of the class described comprising a base having a pair of members extending vertically therefrom and a pump rod passing therethrough, a crank shaft journaled on said members, a cross head slideable on said members, a pitman connecting said cross head and crank shaft and having an extension connected by links to said pump rod for causing a dwell in the movement of said rod at the beginning of its stroke.

3. A pump of the class described comprising a base plate and uprights mounted thereon, a pump rod extending therethrough, a crank shaft journaled on said uprights, a cross head slideable on said uprights, a bell crank having one leg connected to said crank shaft and the other connected by links to said pump rod while its angle portion is connected to said cross head all of which is adapted to cause a dwell in the movement of the pump rod at the beginning of its stroke.

4. A deep well pump head comprising a base and uprights mounted thereon, a crank shaft transversely journaled by the upper ends of said uprights, a cross head slidably mounted on the uprights, a drive shaft carried by said uprights and intermeshing gears on the drive and crank shafts, and a bell crank connected to said cross head and crank shaft and pump rod for causing a dwell in the movement of said pump rod for the purpose set forth.

In testimony that I claim the foregoing I have hereunto set my hand at Fort Wayne, in the county of Allen and State of Indiana. 120

JOHN I. ASTROM.
